CLOCK

Albert N. Woodruff, Washington, D. C.

Application February 13, 1937, Serial No. 125,662

6 Claims. (CL 58—43)

The invention relates to improvements in clocks, and its objects are as follow:

First, to provide the combination of a clock mechanism of any known type and an inherently separate unit which is applied to said clock mechanism as an attachment, the function of the latter being to convert said mechanism into a clock that is operable for determining the time at any desired locality on the globe.

Second, to so locate the thumb-wheels for setting the graduated ring and winding the spring when the clock is of the spring motor type, as to make them easily accessible yet proof against being knocked off readily, said thumb-wheels being made fairly thin but with beveled or rounded edges so as to extend the knurling to which the surfaces are treated.

Third, to distinguish the top surface of the graduated ring with brass and silver or other contrasting finishes, so that the user will know whether the duplicate graduations in the ring half belts are for east or west readings.

Fourth, to provide an attachment having the foregoing characteristics, which is applicable to any known type of clock or watch mechanism merely by mounting it upon the upper plate of the latter.

Other objects and advantages will appear in the following specification, reference being had to the accompanying drawings, in which:

Figure 1 is a perspective view principally of the attachment, but also illustrating how it appears in relationship to a known clock mechanism.

Figure 2 is a detail plan view of a portion of the clock face.

Figure 3 is a cross section of the attachment taken substantially on the line 3—3 of Figure 1.

Figure 4 is a cross section of the known clock mechanism, which figure can also be considered as a supplement to Figure 3, the two views being shown in the relationship in which they will be connected.

Figure 5 is a diagrammatic perspective view, mainly illustrating the parts of the clock attachment, these parts being drawn out of true relationship so that the working can be better understood, and

Figure 6 is a detail plan view of the retaining means for the double-faced gear.

The invention is an improvement on the patent to Albert N. Woodruff, No. 1,990,012 of Feb. 5, 1935. The underlying principle of said patent is preserved in the instant invention, but it has been discovered that there is a need for con-

densing the elements of the patented clock to such an extent as to make of it an inherently separate unit which is capable of being attached to any known type of clock mechanism by merely securing the attachment to the top plate of said mechanism after seeing to it that there is a proper meshing of gears so that the drive of the clock mechanism is carried on through into the attachment.

The instant invention also embodies certain improvements on the patent, all of which are set out below, but before the latter is done it is first desired to describe parts of a known clock mechanism, some of which is disclosed in the patent. The clock mechanism is generally designated 1 (see Fig. 4). This may comprise any known type whether mechanically or electrically driven. The instant showing is that of a mechanical drive in that a spring barrel 2 is involved. The spring motor which this barrel represents is wound through a gear train 3 which terminates at a pinion 4.

It is thought immaterial to set out specifically how the driving power of the spring motor is transferred to the clock mechanism, it being sufficient to point out that said mechanism drives a 12-tooth pinion 10 which meshes with a second-hand gear 11 that is fixed on the second-hand shaft 12. This shaft 12 is common to both the foundation clock mechanism 1 and the attachment 24.

The gear 11 has an integral pinion 13 which meshes with and drives an intermediate gear 14. This gear 11 makes one revolution per minute, and instead of it being driven by the spring motor 2 it can be driven by an electric motor, such as one commonly sees in electric clocks. The staff 15 of the intermediate gear 14 is journaled upon and between the bottom and top plates 16 and 17 of the clock mechanism, said plates being held apart by spacers 18 in a more or less common manner. Reverting to the staff 15, this carries a pinion 19 that is in mesh with a driver gear 20 which is frictionally held upon a sleeve 21 between the friction plates 22. The gear 20 is a slowly rotating gear, making one revolution per hour. The sleeve 21 carries a 12-tooth driver pinion 23, and it is at this pinion that the known clock mechanism ends.

From here on the description of the attachment can be identified in part with the structure of the patent, the improvements being brought out as they occur. The attachment is generally designated 24 (Figs. 1 and 3). Most of the gearing is mounted between a base plate 25 and a dial 55

plate 26. The first gear of the gear train of the attachment is designated 27, and this is a 48-tooth gear in mesh with the driver 23. This first gear is appropriately journaled at 28 on the top plate 17 of the clock mechanism 1 (Fig. 4), advantage being taken of said top plate for this purpose.

The base plate 25 is mounted upon the top plate 17 in any appropriate manner, the usual mode being ordinary screws 29 and spacers (not shown.) When the attachment 24 and clock mechanism are thus assembled, a 12-tooth pinion 30, integral with the gear 27 meshes with the nether component of what is in effect a double-faced, 72-tooth internal gear, actually comprising the two rings designated 31 and 32. Thus far it will be understood that of all the gears which the attachment 24 comprises, the gear 27 is the only one that is mounted on the manufacturer's clock, that is to say, on the clock mechanism as it is bought on the market.

An improvement is to be noted in the 72-tooth gear 31, 32 over its nearest equivalent in the patent. The two rings are separated by spacers 33, although in practice the gear 31, 32 will be made out of a single piece of stock. In making the two gears separate it is readily possible to make the nether one over-size in outside diameter to provide a flange 34 (Fig. 3) to the rim of which retainers 35 are applied as shown. These are attached to the base plate 25, and the latter thus becomes the journal for the gear 31, 32, although actual bearing is confined to lugs 36 which are directed inwardly of a large central opening 37 in the base plate 25 (Fig. 6).

A 12-tooth pinion 38 meshes with the upper component 32 of the so-called double-faced gear. A carrier 39 provides the mount for a shaft 40 on which the pinion 38 revolves in common with an attached 48-tooth gear 41. This gear meshes with and drives a 12-tooth pinion 42 which is part of a tube 43 which extends upward and fixedly carries the minute-hand 44. The double-faced gear 31, 32 rotates once in twenty-four hours and drives the pinion 42, consequently the minute-hand 44, through twenty-four rotations per day and night.

The carrier 39 is secured to a 175-tooth ring gear 45 by means of rivets 46 and spacers 47 (Fig. 3). The ring gear is utilized as a hold-down for the assemblage 39, 45 upon the base plate 25 but having a plurality of retainers 48 supporting its internal circular margin. This 175-tooth ring gear 45 has a cooperative relationship to a similar gear 49 which, however, has only 168 teeth. The latter is what is known as the differential ring gear, and its purpose is to increase the angular speed of a graduated ring 50 over the speed that said ring would have if said ring depended directly upon the ring gear 45 for its setting.

Both ring gears 45 and 49 mesh with an 8-tooth pinion 51. This pinion is carried by a gear 52 which meshes with a setting pinion 53. The shaft 54 of the pinion 53 is journaled in extensions 55 of the base and dial plates 25, 26. Said shaft carries one of a pair of similar thumb-wheels 56, 57.

The thumb wheels are what can be called bump or snag proof. There has been on the market a type of clock, intended especially for aviator's use which has a setting wheel protruding upwardly above the clock face. The accidental knocking off of some of these setting knobs has resulted in the condemnation of all clocks of the type in mind, and inasmuch as it is desirable to have the in-

stant thumb-wheels in easily accessible positions, the structural arrangement shown has been adopted to reduce to a minimum the possibility of their being knocked off. As seen in Fig. 3 the thumb-wheel 56, making reference to only one, is fairly thin. It will stand well below the glass when in place. The upper edge is either rounded or beveled at 58. This materially expands or widens the surface to which the knurling 59 is applied. Therefore the operator can very readily drag his finger over such surface as may be adjacent to the thumb-wheel 56 and procure an entirely adequate bearing upon the margin of the thumb wheel, the knurled surface of which has been broadened in the manner indicated, despite the fact that it is very thin as compared with known types of setting knobs.

The purpose of the pinion 53, an equivalent of which does not occur in the patent, is to dispense with the rather large thumb-wheel of the patent, and at the same time make a gain in the leverage by which the companion ring gears 45, 49 are actuated. While on the subject of the thumb-wheels, it will be noted that 57 has its shaft 60 journaled in extensions 61 of the plates 25, 26. This shaft reaches down and carries the pinion 4 which actuates the train 3 for winding the motor 2.

A tube 62 revolves upon the tube 43. The former carries the hour-hand 63 and it has a 40-tooth gear 64 which meshes with a 10-tooth pinion 65 which is integral with a 36-tooth gear 66 that meshes with the pinion 42 and revolves upon a shaft 67 which depends from the dial plate 26. The latter also carries an 8-tooth idler 68 which meshes with and drives an 80-tooth day-night ring gear 69. A small portion of the upper surface of the ring is visible in a window 70 in the dial plate 26, in respect to which it is turnably supported by headed retainers 69a (Fig. 2) depending from the nether side of the dial plate. The entire upper surface is divided into black and white halves 71, 72 (Fig. 5) indicating periods of time after 12 o'clock noon (P. M.) and after 12:00 o'clock midnight (A. M.). Fig. 2 illustrates the change in the indication of the ring 69 shortly after 12:00 o'clock noon. The shaft 12 to which reference was made near the beginning, extends through the central tube 43 and carries the second-hand 73.

Reverting to the ring 50, it is seen in Fig. 5 that its upper surface is graduated at 74 in degrees beginning at zero and numbered to 180, reading both ways, thus serving as an index as to how far to move the ring. These graduations are visible through a second window 75 in the dial plate 26. The graduations indicate the degrees of longitude west and east of Greenwich, and in order that the observer may know whether he is looking at the graduations in the western or eastern zone, the top halves of the ring surface are contrasted by brass and silver finishes 76 and 77. In practice other contrasting finishes may be adopted, but the brass and silver combination is regarded as of especial advantage because of the ease with which one can be distinguished from the other.

Little has to be added to the description of the dial plate 26. The American public, including aviators, navigators, and the like, are 12-hour dial conscious, hence the necessity of using the 12-hour dial 78 shown. The markings on this dial are supplemented by designations 79 and 80, respectively, comprising the letters E and W with arrows, each of which points to the window 75. 75

The designations are located on opposite sides of the window, and they are intended to guide the user in moving the graduated ring 50 when he manipulates the thumb wheel 56.

5 The operation is readily understood. First, by way of a brief review, it is desired to remind the reader, as set out in the patent, that the fundamental invention is to provide a clock which will continuously tell the local time, and which can be simply adjusted so that its hour-hand and minute-hand will indicate the time on its dial at any remote point on the globe. This facility is of especial advantage to persons who navigate vessels and pilot aircraft and have occasional need 10 for knowing the exact time, whether of day or night, of the locality in which they are situated or toward which they are traveling. It is commonly known that as far as the United States is concerned the country is separated into divisions 15 having Eastern standard time, Central standard time, Mountain standard time and Pacific standard time.

The time belts are spaced approximately 15° apart, and if one crosses the lines dividing these 25 belts, the current practice is to set the timepiece either backward or forward, depending on whether the direction of travel is west or east. According to this plan any given hour is adopted 30 as the hour in the entire zone between any two hour meridians. For instance, if the time is 2:00 P. M. in Washington, D. C. it is also 2:00 P. M. anywhere in the zone between the 75° and 90° meridians. While this is satisfactory for general 35 working purposes yet it does not acquaint a person with the exact time at points intermediately of the meridians, which time, obviously, will vary for every fraction of distance one way or the other.

To begin with the clock mechanism 1 (Fig. 4) is supposed to be functioning correctly so that the hands 44, 63 are telling the correct time. These hands are capable of being set independently of the clock mechanism, and it is to enable 40 this independent setting that the driver gear 28 is supplemented with the friction plates 22. In practice a hand-setting wheel (not shown) can be geared to the first gear 27 of the attachment for accomplishing the purpose in mind, thus 45 constituting the first mode of setting the hands.

50 The second mode of operating the hands is through the normal functioning of the spring or other motor 2 and the gear train driven thereby. Counterclockwise turning of the gear 27 and pinion 30 (Fig. 4) causes counterclockwise turning of the double gear 31, 32 because of the meshing of the pinion 30 with the ring gear 31. The unit 33, 41 (Fig. 3) is stationary relatively to the ring gear 45 because said unit is attached to the carrier 39 which is virtually an integral part of said ring gear. This ring gear as well as the differential gear 49 and its graduated ring 50 remains 55 stationary during the normal operation of the clock.

60 Since the double gear 31, 32 is being turned counterclockwise because of the counterclockwise turning of the pinion 30, the unit 33, 41 is also turned counterclockwise by virtue of its pinion 38 meshing with the upper ring gear 32.

65 The counterclockwise turning of the gear 41 causes clockwise turning of the pinion 42, counterclockwise turning of the gear 66 and clockwise turning of the gear 64. The tube 43 of the pinion 42 moves the minute-hand 44 one dial rotation each hour, while the double reduction of the gear 70 train 42, 66, 65 and 64 turns the tube 62 of hour-

hand 63 $\frac{1}{2}$ of the dial circumference per hour. At the same time the day-night ring gear 69 rotates at the rate of $\frac{1}{4}$ of the dial circumference per hour, the result being that the white zone stays in view of the window 70 for the twelve 5 A. M. hours and the black zone stays in view for the twelve P. M. hours.

The third mode of operation of the clock occurs when it is desired to determine the exact time at any designated remote locality. The instant 10 calculation is made from Washington, D. C. which is located near the 77° meridian west longitude (west of Greenwich). This or any other meridian reading is ascertained from any map having thereon notations of the degrees E and W of 15 Greenwich. The hands 44, 63 must first indicate the exact local time, and it is herein supposed that the time for Washington, D. C. is 8:00 A. M. Now manipulate the thumb-wheel 56 to turn the ring 50 beneath the window 75. Suppose that it 20 is desired to know the corresponding time in Honolulu, Hawaii. Honolulu is situated between the 150° and the 165° meridians. Since Honolulu is west of Washington, D. C. the thumb-wheel 56 must be turned counterclockwise, this 25 agreeing with the direction of the arrow adjacent the designation W which indicates west. The graduated ring 50 will correspondingly turn counterclockwise, and when the brass finish 76 (Fig. 5) shows at the window the user will be put on 30 guard to watch for the 150° graduation. When this graduation lines up with the vertical center through the window 75 the clock hands will indicate 3:00 A. M., and that is caused in this way:

35 As the thumb-wheel 56 is turned counterclockwise the pinion 51 (Fig. 3) causes simultaneous counterclockwise turning of the ring 50, differential gear 49 and gear 45. Since the unit 38, 41 is carried by the latter, and the double gear 31, 32 is incapable of turning because of the resistance of 40 the gear train behind it, it follows that said unit 38, 41 will partake of a planetary motion around the double gear, turning clockwise all the while by virtue of its pinion 38 meshing with the gear 32.

Clockwise turning of the gear 41 causes 45 counterclockwise turning of the pinion 42 and of its carried minute-hand 44, also counterclockwise turning of the gear 64 and of its carried hour-hand 63. The clock hands are thus set back, the time indicated being earlier the farther west the 50 reading is taken.

However, it was stated that Honolulu lies between the 150° and the 165° meridians west longitude. Actually it is located on a line approximately 157° W. The thumb-wheel 56 is turned a 55 little farther counterclockwise until the 157° graduation lines up with the center of the window 75. The clock hands will be retarded a little more, designating 2:32 A. M. which is the exact time reading at Honolulu when it is 8:00 A. M. at 60 Washington, D. C.

The necessity for the differential gear 49 is to make the graduated ring 50 traverse the window 75 a little faster than it would if it were carried directly by the ring gear 45. Since the gear 49 65 has fewer teeth than the gear 45 it will turn faster by 15° in one revolution than the gear 45, thereby insuring 360° of angular movement of the ring 50 with the clock hands at the end of a 24-hour cycle. If the clock hands were manually turned 70 through this cycle it would so happen that operation would have to continue until the passage of 25 hours before the graduated ring 50 would traverse the 360° zone.

I claim:

1. A clock comprising hour- and minute-hands, clock mechanism for turning the hands, a numbered dial traverseable by the hands, said dial having a window, a ring gear in mesh with and driven by said clock mechanism, the top surface 5 of said ring gear being divided into half zones designating day and night, and means depending from the nether side of the dial supporting said ring gear in turning relationship to the window so that zones become alternately visible.
2. A clock comprising hour- and minute-hands, clock mechanism for turning the hands, a dial plate traversable by the hands and having two windows, a ring gear in mesh with and driven by 10 the clock mechanism, the upper surface of said ring gear being arranged to indicate day or night in accordance with the time designated by the hands, means depending from the dial plate supporting said ring gear in turning relation to one 15 of the windows, graduated means which is normally independent of the clock mechanism and has graduations representing divisions of longitude on the globe, means for turnably supporting said graduated means from the dial plate so that 20 the graduations appear at the second window, and manually operable means for moving the graduated means and simultaneously moving the hands and said day-night ring gear so that they 25 traverse the dial plate irrespective of said clock mechanism.
3. A clock which includes a dial plate, hour- and minute-hands, and a clock mechanism by which they are made to traverse said plate, means to adjust the hands independently of the clock 30 mechanism including a shaft journaled in the plate, and a thumb-wheel fixed on the shaft close to and above the dial plate, said thumb-wheel being thin as compared to its diameter so as to project only a short distance above the dial plate, 35 but having the top edge flattened and roughened to present a broad contactible surface.
4. In a clock, a base plate which has an opening with projections, a driver pinion extending through said opening, a double gear consisting of two ring gears and means by which they are 40 secured together, the lower ring gear being larger than the upper to provide a flange riding on said projections around said opening in position for meshing engagement by said pinion, means car-
- ried by the base plate with which said flange engages to turnably retain the double gear, and a pinion in driving engagement with the upper ring of said gear.
5. A clock comprising a dial plate which has a 5 window, the clock face of said plate having indicia adjacent to the window denoting east and west longitude, clock mechanism terminating in hour and minute-hands which are in position to traverse the clock face, and means by which to 10 set the hands in respect to the clock face and independently of the clock mechanism to determine the time at a locality remote from the one at which the clock is situated, said means including a ring which is movable beneath the window and 15 has markings graduated from zero to 180° running in opposite directions, the sectors of the ring with the respective markings having contrasting finishes to agree with the respective indicia on the clock face so that the user can tell 20 whether the adjustments are made in east or west longitude.
6. A clock comprising a standard clock mechanism including a top plate, driven gearing also included in said mechanism ending in a terminal 25 driver pinion on top of said plate, an attachment for converting said clock mechanism into an instrumentality whereby to designate the time at a remote locality, said attachment comprising a gear train revolvably affixed to said top plate and 30 including a gear in mesh with said driver pinion, said gear train including a pinion integral with said gear, a shaft common to the clock mechanism and said attachment and providing a journal for said driver pinion, said attachment including 35 clock hands usually possessed by said mechanism, one of the hands being carried by said common shaft, and instrumentalities for manually adjusting said hands independently of the clock mechanism, said instrumentalities including graduated 40 means which has graduations representing divisions of longitude on the globe, a dial plate which is traversable by the hands, and means for moving the graduated means so that its graduations can be inspected with respect to a fixed point in order 45 to tell when to stop the manual operation of the hands.

ALBERT N. WOODRUFF.
